Joseph O. Cadieux

ATTORNEY

UNITED STATES PATENT OFFICE.

JOSEPH O. CADIEUX, OF MERIDEN, CONNECTICUT, ASSIGNOR TO THE CONNECTICUT
TELEPHONE & ELECTRIC COMPANY, INCORPORATED.

SIGNAL SWITCH.

Application filed June 28, 1923. Serial No. 648,213.

To all whom it may concern:

Be it known that I, JOSEPH O. CADIEUX, a citizen of the United States of America, residing at Meriden, Connecticut, have invented a new and useful Signal Switch, of which the following is a specification.

My invention relates particularly to switches for annunciator or call systems such for instance as are employed in hospitals and the like, but it will be obvious that the invention is applicable to other uses. One object is to provide a simple and reliable form of construction in which the circuit is normally opened and which is automatically locked when the circuit is closed, but which may be manually released when desired.

Another object is to provide in such a construction means to enable the operator to flash a signal which has been set.

Another object is to permit the alternate operation of two types of signals.

Another object is to so relate the circuit closing button to the latch mechanism that the latch may be readily operated by the end of the finger but so that there is practically no likelihood of accidental release.

Figure 1 is a side view and partial section showing a construction embodying improvements of my invention and with a diagram of one circuit arrangement.

Fig. 2 is a rear end view.

Fig. 3 is a front view.

Fig. 4 is a longitudinal sectional view of the base and contacts and showing a spring detached.

Fig. 5 is a side view of the movable contact carrier and operating member.

Fig. 6 is a side view of the frame and a part of the latch and release member.

Fig. 7 is a transverse sectional view of the part shown in Fig. 6.

Fig. 8 is a perspective view of an auxiliary contact member.

Fig. 9 is a detail view showing a modified form of auxiliary contact.

The base 10 of insulating material and may be of any shape depending upon the method of mounting.

A plurality of spring contact fingers such as 11, 12, 13 and 14 are provided and suitably secured to the insulating base and provided with any suitable form of circuit terminals. While I have shown four of these

contact fingers, it should be understood that 55 the preferred construction has at least two and may have any greater number. Certain features of the construction, however, are not limited to any particular number of contacts.

The movable contact 15 in the construction shown is in the form of a ring carried by the insulating button 16 so that the circuit is normally open. The push button operating member 17 of insulating material 65 is connected to the insulating member 16 and projects through a face plate 18 in which it is guided. This face plate 18 may be of any suitable design or construction depending upon the external form which 70 the switch is to have. For convenience in construction and assembly a frame 19 is secured to the insulating base 10 and carries the end or face plate 18 which may conveniently be secured to it by means of 75 an eyelet 20 which provides the guiding surface for the push button.

The spring 21 which is interposed between the base 10 and the insulating member 16 serves to hold the parts in their normal 80 open circuit relation as shown in Fig. 1, at which time the shoulder 22 at the inner end of the push button abuts against the inner side of the face plate or the guide member 20. When the push button is 85 pushed in, the contact member 15 connects the ends of all the contact fingers.

In the preferred form of construction I provide a latch consisting of the head 23 and the slide 24. The movable contact 15 90 is insulated from the slide 24 by a washer 16' which also serves to yieldingly check the return movement against the slide. The slide has ends 25 guided in the sides of the frame 19. The spring 26 yieldingly holds 95 the slide in the position shown in Figs. 1 and 6. The inner face of the head 23 is preferably inclined so as to thrust the slide 24 aside as the head passes through the opening in the slide. As soon as the head 23 has passed through the slide plate 24, the spring 26 will snap the slide plate back behind the shoulder of the head 23 and hold the parts in the closed circuit position.

The contact member may be released by 105 pressing on the end 25 to slide it sufficiently to release the head 23 from the slide. I prefer, however, to provide an operating

member 27 which is in the form of a leaf spring which extends through the frame 19 and has a finger piece 28 in a depression or recess 29 in the face plate. Normally the 5 parts stand in the position of Figs. 1 and 6 and the latch release member 28 is in the same position whether the circuit is open or closed. When the circuit is open the push button 17 projects "out" its maximum 10 extent and when the circuit is closed the push button is "in." To release the switch when the circuit is closed it is simply necessary to grasp the end 18 with two fingers while the finger piece 28 is operated by the 15 end of a third finger moving it toward the push button. The motion to release being entirely different from the setting motion, there is no danger of the switch being released accidentally at the instant of setting. 20 By having the finger piece 28 partially or completely housed within the recess 29 accidental contact and release are prevented. A lug 30 may be secured to the release member 27 immediately back of the front end of 25 the frame 19 to cover the opening through which the finger piece 28 extends.

In addition to the contacts above described I prefer to provide additional contacts for an auxiliary or emergency signal circuit. In 30 to form shown in Figs. 1 and 4 I provide a center contact 31 suitably mounted in the base and a washer-like member 32 which surrounds the member 31 but does not engage it. This member 32 is electrically connected with the contact member 11 and the base of spring 21 presses against it when the parts are assembled. The movable insulating member 16 carries an auxiliary contact member 33 which is in the form of a 35 collar carrying a spring contact element 34. This auxiliary contact may be mounted on a split sleeve portion 35 of the insulation. The outer end of the spring 21 abuts against the collar 33. When the operating member is 40 pushed in, the contact strip 34 engages the end of the stationary contact 31. When the operating member is pushed in sufficiently far the edge of the insulating cylinder 16 engages the humped shoulder 36 on the contact spring 11 and pushes it outward into 45 the position shown by dotted lines in Fig. 4.

A typical circuit arrangement is shown in the diagram of Fig. 1 where the contact 11 is shown connected to one side of a source 50 of E. M. F. A signal device such as a device 37 is connected between each of the other contacts 12, 13 and 14 and the opposite terminal of the source. It is obvious that when the operating member is pushed 55 in and the contact 15 engages the ends of the spring contact fingers the circuit will extend through the contact finger 11 to contact 15 and thence to each of the other contact fingers simultaneously lighting all of 60 the signal lights 37. When the insulating 65

member is pushed in to the position shown in Fig. 4 the contact finger 11 is pushed away from the contact 15 and all the circuits are simultaneously broken. By pushing in on the button 17 it is thus possible to flash all 70 the signal lights. When the center contact 31 is engaged or the operating member is pushed in sufficiently far, the contact strips 34 engage the contact 31 and the auxiliary or emergency circuit, for instance through 75 the buzzer 38, is completed (11, 32, 21, 33, 34, 31). When this buzzer circuit is completed the insulating member 16 is in the dotted position of Fig. 4 and the contact finger 11 is off the contact 15. The lights 80 are therefore out when the buzzer is on. This is not only an advantage in giving a characteristic emergency signal but it also prevents the drain on the source of power which would occur were the buzzer and 85 lights all thrust on at the same time.

In Fig. 9 I have shown a modified form of auxiliary circuit closing device in which the center contact 31 and the contact elements 33 and 34 are omitted. In this case 90 the auxiliary buzzer contact 40 is mounted in such a position as to be engaged by the tip 41 of the contact member 11 when the insulating button 16 has lifted the tip away from the contact 15. By such a construction 95 it is possible to obtain a similar alternate operation of the main signal devices and the auxiliary or emergency signals.

The construction shown in Fig. 9 of this application is claimed specifically in my application 1536 filed January 10th, 1925.

I claim:

1. In a switch, a base, a plurality of contact fingers projecting therefrom, an insulating member slidable between said fingers, a contact member carried thereby to engage said fingers, a face plate, a push button connected to said insulating member and guided in said plate, an auxiliary contact adapted to be electrically connected to one of said contact fingers, and means carried by said insulating member for moving said latter finger away from said contact member and electrically connecting it with said auxiliary contact.

2. In a switch, an insulating base, a plurality of contact fingers projecting therefrom, an insulating member slidable between said fingers, a contact member carried thereby to engage said contact fingers, a push button connected to said insulating member, an auxiliary contact and means carried by said insulating member for moving one of said fingers away from said contact member and electrically connecting it with said auxiliary contact.

3. In a switch, a base, a spring contact carried thereby, a center contact, a reciprocable insulating member having two contact members, one of which is adapted to

- engage said spring contact, and the other of which is adapted to engage said center contact, and a spring connecting said spring contact with said second contact member.
- 5 4. A switch, a spring contact, a stationary contact, a reciprocable insulating member, a contact member carried thereby adapted to engage said stationary contact, said insulating member and said spring contact having cooperating portions whereby said reciprocable member is adapted to move said spring contact laterally when said contact member engages said stationary contact.
- 10 5. In a switch, an insulating base, a stationary contact pin projecting therefrom, a spring arm contact carried by said base at one side of said pin, a plunger reciprocable on said pin, a contact carried by said plunger and adapted to engage said spring arm contact and a contact carried by said plunger and adapted to engage said contact pin within said plunger.
- 15 6. In an electric switch, a frame, a face plate carried by one end of said frame, an insulating base carried by the other end of said frame, a plunger having a push button guided in said face plate, a contact carried by said base, a contact carried by said plunger adapted to engage the contact carried by said base when the plunger and push button are pushed in, a sliding latch member transversely movable in said frame adapted to automatically engage said plunger to hold it in one position, said latch member having one end projecting beyond one side of said frame for lateral engagement to facilitate release of said latch member and plunger.
- 20 7. In an electric switch, an insulating base, a U-shaped frame having side bars secured to said base, a face plate at the opposite end of said frame, a tubular rivet connecting said face plate with said frame and a contact carrying plunger having a push button operator guided in said tubular rivet.
- 25 8. In a switch, an insulating base, a stationary contact member carried thereby, a reciprocable member having a sleeve adapted to move axially of said contact and a spring contact carried by said reciprocable member within said sleeve.
- 30 9. In a switch, an insulating base, a terminal at one side thereof, a center contact element, an electrically connecting member secured to said base and electrically connected to said terminal and having a portion arranged at one side of said center contact element, a contact member reciprocable with respect to said center contact element and a spiral spring interposed between said contact member and said base.
- 35 10. In a switch, an insulating base having a spring contact at one side, a central contact, a spring surrounding said central contact and electrically connected to said spring contact, two contact members reciprocable with respect to said base, one of said contact members being electrically connected to said spring and the other adapted to engage said spring contact when said first mentioned contact member is out of contact with said central contact.
- 40 11. In a switch, a plurality of stationary contacts, a movable contact member reciprocable between said stationary contacts, a push button for operating said movable contact member, a face plate guiding said push button, and means for establishing an auxiliary circuit when said push button is operated and simultaneously opening the circuit through said contacts so as to intermittently and alternately open and close the circuits, a latch for said movable contact member and a release member arranged in said face plate alongside of said push button and movable towards said push button to release said contact member.
- 45 12. In a switch, a stationary contact, a movable contact member, a face plate, a push button guided therein for operating said movable contact member, a latch for said contact member for holding it in the closed circuit position, a spring tending to move said contact member to open circuit position, a release member having an operating finger piece let into the surface of said face plate alongside of said push button and operable by movement in a direction radial to said push button to release said latch.
- 50 13. In a switch, an insulating base, a central buzzer contact, a plurality of outer light contacts, a main movable contact member for connecting said light contacts, an auxiliary contact member for engaging said buzzer contact, one of said light contacts being laterally movable away from said movable contact and connected to the buzzer contact and manually operable means for moving said movable contacts toward said buzzer contact and said light contacts respectively and for moving said laterally movable contact away from said main movable contact member.
- 55 14. In a switch, a base, a plurality of contact fingers arranged around said base, a center contact carried by said base, a reciprocable member, two contact members carried thereby and co-acting respectively with the contacts carried by said base and a spring surrounding the center contact and connecting one of said fingers to one of said contact members.
- 60 15. In a switch, an insulating base, a terminal and a stationary contact member carried by said base, a reciprocable member having a sleeve adapted to move axially of said contact member and a spring contact carried by said reciprocable member within

said sleeve and a spring surrounding said sleeve and connecting said spring contact and said terminal.

16. In an electric switch, a guide pin contact, a plunger having a split sleeve slidable on said pin contact, a collar surrounding a portion of said sleeve and a contact strip embracing said collar and having a yielding end projecting into said sleeve and adapted 10 to engage said pin contact.

17. In an electric switch, an insulating base, a guide pin contact carried thereby, a plunger operable on said guide pin contact, a collar carried by said plunger and a 15 contact member embracing opposite edges of said collar and having spring arms projecting inside of said collar and adapted to engage said guide pin contact.

18. In an electric switch, an insulating base, a guide pin contact projecting therefrom, a spring arm contact secured to one side of said base, a plunger reciprocable on said guide pin contact, a contact member carried by said plunger and adapted to engage such spring arm contact, a second contact carried by said plunger and adapted 25 to engage said guide pin contact and means carried by said plunger for engaging said spring arm contact and moving it away 30 from the co-acting contact on said plunger.

19. In an electric switch, an insulating base, a face plate, longitudinally extending side bars connecting said face plate to said base, spring contact fingers projecting from 35 said base towards said face plate, a plunger having a contact reciprocable between said contact fingers, a latch plate co-acting with

said plunger and having its opposite ends guided in said side bars and a spring operating arm secured to said base beneath one of 40 the side bars and having one end engaging said latch plate.

20. In an electric switch, an insulating base, a contact pin guide carried by said base, a spring arm contact carried by one 45 side of said base, a plunger reciprocable on said contact pin guide, a contact carried by said plunger adapted to engage said spring arm contact, a spring normally holding said plunger in position with the contact member 50 free from contact with said spring arm contact, a manually releasable latch for automatically engaging said plunger to hold it yieldingly in position with its contact member in engagement with said spring arm 55 contact, a second contact carried by said plunger adapted to engage said contact pin guide and means carried by said plunger for engaging said spring arm contact and disengaging it from the corresponding contact of said plunger when the other contact of the plunger engages said pin.

21. In an electric switch, an insulating base, a guide pin embedded in said base and having one end projecting therefrom and a binding screw at the opposite end, a spring arm contact secured to one side of said base and having a binding screw accessible at the side, a plunger guided on said pin and having inner and outer contacts respectively for engagement with said pin and with 65 said spring arm contact.

JOSEPH O. CADIEUX.
